DISPENSER FOR ROLLED SHEET MATERIAL

Ray O. Wilson, Los Angeles, Calif., assignor of
one-half to Russell E. Walsh, Gardena, Calif.

Application August 18, 1941, Serial No. 407,331

12 Claims. (Cl. 242—55.5)

My invention relates to a dispenser for rolled sheet material and has particular reference, to a dispenser for rolled paper toweling and similar paper products.

The conventional forms of dispensers for rolled paper toweling include a means for arresting the feeding of the toweling from the cabinet whenever a predetermined length of toweling has been withdrawn and include also cutters or other means permitting the removed length to be severed from the roll. Thus the toweling is dispensed from a continuous roll of material in the form of relatively short lengths or individual towels.

The most desirable length for such a towel is determined principally by the conditions under which such towels are dispensed. For example, in connection with the operation of gasoline service stations it has become the practice to employ towel dispensers in the rest rooms and wash rooms and also at the "island" or gasoline pump location, these latter dispensers being used to dispense paper towels which are employed for the cleaning of automobile windshields. It has been found that a ten or eleven inch towel will adequately supply the towel needs in wash rooms and rest rooms but that such a relatively short towel is absolutely inadequate for use in cleaning windshields, this latter operation requiring generally a towel of approximately twenty inches in length. For obvious reasons it is desirable to employ the same towel dispenser at the "island" or pump location as is employed in the wash rooms, but prior to my invention there has not been made available a towel dispenser which can be readily adjusted to provide substantially any desired length of individual towel.

In connection with the use of towel dispensers at gasoline service stations, it is desirable that the dispensers which are located in the wash rooms and rest rooms be provided with a manually operable device for releasing the towel stop so that after one towel length has been withdrawn from the cabinet a manual operation of the control device is required before another towel can be withdrawn. By employing such a device the wasting of towels is discouraged and a considerable economy in the towel consumption is realized. However, where a towel dispenser is employed at the "island," the requirement for releasing a manual control device before a towel can be withdrawn is an unnecessary nuisance. In order to assist a service station operator in providing quick service and to avoid delays, it is desirable that a towel may be withdrawn from

the dispenser at any time without the need of manipulating levers or similar release devices in order to permit the withdrawal of a towel. Prior to my invention, no towel dispenser was available which could be readily and easily arranged for automatic operation as is desired at the "island" or for manual operation as is required when the dispenser is installed in the wash rooms.

It is, therefore, an object of my invention to provide a dispenser for rolled sheet material in which a stop is provided for arresting the movement of the sheet material each time a predetermined length of sheet material is drawn from the roll, together with a means which is automatically responsive to the severing of the withdrawn length of towel for removing the stop to permit another length to be withdrawn from the dispenser.

It is also an object of my invention to provide a dispenser of the character set forth in the preceding paragraph in which a means is provided for preventing the operation of the automatic releasing means and including also a manually operable means for effecting the release of the stop.

It is an additional object of my invention to provide a dispenser of the character set forth in the preceding paragraphs wherein at least a part of the weight of the roll of sheet material is rested upon a roller over which the sheet material is passed as it is withdrawn from the roll and in which the roller is spring urged in one direction and movable a predetermined distance in the opposite direction in response to withdrawing of the sheet material.

It is also an object of my invention to provide a dispenser of the character set forth in the preceding paragraph in which a means is provided for disengaging the roll of sheet material from the roller to permit the spring to return the roller to its original starting position to thereby permit another length of sheet material to be withdrawn from the dispenser.

It is a still further object of my invention to provide a dispenser of the character set forth in the preceding paragraphs which includes a means for adjusting the length of material which may be withdrawn before movement of the material is arrested by the stop means.

It is also an object of my invention to provide a dispenser of the character set forth hereinbefore in which the means for adjusting the length of the withdrawn material is enclosed within the dispenser to discourage unauthorized adjustment thereof.

Other objects and advantages of my invention

will be apparent from a study of the following specifications, read in connection with the accompanying drawings, wherein:

Fig. 1 is a perspective view illustrating the form and appearance of the preferred form of my invention;

Fig. 2 is an end elevational view of the dispenser illustrated in Fig. 1 with the lower part of one end plate broken away to illustrate the interior arrangement of the mechanism;

Fig. 3 is a fragmentary vertical section taken substantially along the line III—III of Fig. 2;

Fig. 4 is a fragmentary cross sectional view taken substantially along the line IV—IV of Fig. 3 to illustrate the operative positions of the parts at the time a length of sheet material is being withdrawn from the dispenser;

Fig. 5 is a view similar to Fig. 4 but illustrating the positions of the parts after the withdrawn length has been severed from the roll of material;

Fig. 6 is an enlarged fragmentary sectional view of the right-hand end portion of the mechanism illustrated in Fig. 3;

Fig. 7 is a fragmentary cross sectional view taken substantially along the line VII—VII of Fig. 6; and

Fig. 8 is a fragmentary sectional view taken substantially along the line VIII—VIII of Fig. 3.

Referring to the drawings, I have illustrated in Fig. 1 the preferred embodiment of my invention as comprising a cabinet 1 which is fitted with a hinged cover 2, the cover 2 being pivotally supported upon the cabinet 1 as by means of hinge or pivot pins 3. The cabinet is employed to enclose a roll 4 of sheet material which is supported in the cabinet by means of a control roller 5 and a tiltable shelf 6. The roller 5 is extended across the cabinet 1 parallel to the axis of the roll of material 4 and is so positioned with respect to the roll 4 as to support at least a part of the weight of the roll.

The end of the roll of material 4 indicated in the drawings by reference character 6a is passed over the top of the roller 5 and thence downwardly past a guiding shoe 7 which is suitably supported as by means of clips 8 from the cover 2 and through a suitable aperture 9 formed in the bottom of the cabinet 1. When the end 6a of the sheet material is grasped and pulled from the cabinet, the roller 5 will be rotated thereby, the roller 5 being journaled for rotation upon a shaft 10 which is extended between and supported by opposite end walls 11 and 12 of the cabinet 1.

The shaft 10 is preferably provided with a squared end portion 13 which is received in a similarly squared aperture provided in a hub portion 14 of an adjustment lever 15. The lever 15 includes a detent 16 normally engaged with one of a plurality of apertures 17 formed in an adjustment plate 18 which is in turn secured as by soldering or spot welding 19 to the inner surface of the cabinet end wall 11. Thus the shaft 10 is non-rotatably supported from the cabinet end wall 11.

The roller 5 may be journaled for rotation upon the shaft 10 as by providing the roller 5 with a longitudinally extending bore 20 fitted with suitable journals or bushings 21 and 22 rotatably received upon the shaft 10. The opposite end of the shaft 10 is preferably reduced in diameter as indicated at 23 (see Fig. 6), this reduced diameter end being received in a corresponding bore 24 formed in a track defining

member 25. The member 25 is preferably provided with an outer squared end 26 which is received in a similarly squared aperture 27 formed in an end bracket 28 which is in turn suitably secured to the inner surface of the cabinet end wall 12. The track defining member 25 preferably comprises a cylindrical member in the outer surface of which is cut a helical groove 29 which has an arcuate cross section adjusted to closely conform to the curvature of a steel ball 30 which is mounted for movement along the helical groove.

The ball 30 is caused to move along the groove 29 in response to rotation of the roller 5, the aperture 20 in the roller 5 being enlarged as indicated at 31 in Fig. 6 and fitted with a sleeve 32. The sleeve 32 is of generally cylindrical form but includes an axially extending and radially deformed portion 33 which, together with the groove 29, encompasses the ball 30 and serves to retain the ball 30 within the groove 29 and serves also to move the ball 30 circumferentially of the member 25 as the roller 5 is rotated. As the roller 5 is rotated, the ball 30 is thus moved along the helical groove 29 and is thus caused to move axially of the roller 5 from an initial position such as that illustrated in Fig. 3 to an arresting position such as that illustrated in Fig. 6 in which the ball 30 engages a radial flange 34 formed on the track defining member 25.

When the ball is moved to the position illustrated in Fig. 6 further rotary movement cannot take place without similarly rotating the member 25 which is held against such rotation by engagement of the squared end 26 with the squared aperture 27. Thus, the roller 5 is permitted a predetermined limited number of revolutions in moving the ball 30 from the position illustrated in Fig. 3 to that illustrated in Fig. 6. This rotation is imparted to the roller 5 by the withdrawal of the sheet material which is frictionally engaged with the roller 5, such frictional engagement being enhanced, if desired, by the employment of suitable sleeves or bands 35 of rubber or other friction material surrounding the roller 5. Thus when the rotation of the roller 5 is arrested, the withdrawal of the sheet material is likewise arrested and when this condition obtains, the withdrawn length may be severed by lifting the withdrawn length outwardly and upwardly to bring the same into engagement with a serrated cutting edge 36 which is carried by the cover 2.

It will be noted that the length of the piece of material thus severed from the roll 4 is determined by the length of path through which the ball 30 is permitted to move. The limits of the path of movement of the ball 30 is defined at one end by the radial flange 34 and at the other end by an end 31 of a helical spring 38 which is wound about the end of the shaft 10 and in the helical groove 29. The opposite end of the spring 38 is turned inwardly as indicated at 39 and engaged with a longitudinally extending keyway 40 formed in the end of the shaft 10.

It will be noted that by rotating the shaft 10, the spring 38 will be rotated relative to the track defining member 25. The spring 38 is closely fitted in the helical groove 29 so that such rotation of the spring 38 will result in an axial movement of the spring relative to the shaft 10 and member 25, this axial movement being permitted by the sliding of the in-turned end 39 along the keyway 40. Such movement of the spring

38 obviously serves to lengthen or shorten the helical path through which the ball may be moved and consequently serves to adjust the number of rotations which is permitted of the roller 5 and the length of material which may be withdrawn before the ball 30 is engaged with the stop 34.

The adjusting lever 25 is provided for rotating the shaft 10, such rotation of the shaft 10 being permitted by forming the same with a cylindrical end portion 41 which is received within a circular aperture provided in the adjustment plate 18. The detent portion 16 of the lever 15 may be disengaged from the aperture 17 by springing the lever 15 inwardly. In moving the lever 15 to a new position a release of the inward pressure thereon permits the detent 16 to engage another one of the apertures 17 and thereafter hold the shaft 10 against subsequent rotation.

The roller 5 is normally urged to rotate in a direction opposite to the direction of rotation imparted by the withdrawal of the sheet material 4. This may be accomplished by counterboring one end of the bore 20 as indicated at 42 and providing a torsion spring 43 within the counterbore 42 encircling the shaft 10, one end of the spring 43 being engaged with the roller 5 as indicated at 44 and the other end being engaged as indicated at 45 with an enlarged portion 46 formed on the shaft 10. This spring is tensioned by the rotation of the roller 5 resulting from the withdrawal of the material from the dispenser and tends to rotate the roller 5 in the reverse direction. This reverse rotation is, however, prevented by the weight of the roll 4 resting on the roller 5 and the frictional engagement of the end 6a of the material with that portion of the roller surface with which it is engaged.

To permit an additional length of sheet material to be withdrawn from the dispenser it is necessary that this frictional engagement between the sheet material and the roller be removed to permit the roller 5 to return to its initial position as is illustrated in Fig. 3. The tiltable shelf 6 is employed for effecting this releasing operation and accordingly includes a plurality of curved fingers 47 which partially encircle the roller 5 and are disposed between the roller 5 and the sheet material 6a. The fingers 47 normally do not engage the sheet material 6a, being received within circumferentially extending grooves 48 formed in the outer surface of the roller 5.

The shelf 6 is pivotally supported within the cabinet 1 as by means of a transversely extending pivot pin 49 and pivotal movement of the shelf 6 about the pivot pin 49 from a position such as that illustrated in Fig. 4 to a position such as that illustrated in Fig. 5 serves to raise the fingers 47 and bring the same into contact with the sheet material 6a and lift the same out of engagement with the roller 5. At the same time the roll 4 of sheet material is lifted and moved rearwardly out of engagement with the roller 5, thus freeing the roller 5 and permitting the torsion spring 43 to return the same to its initial position as is illustrated in Fig. 3.

Tilting movement of the shelf 6 is preferably limited between positions illustrated in Figs. 4 and 5 by a suitable stop construction. One convenient form of stop construction is illustrated herein as comprising a member 50 which is secured to the shelf 6 and extended laterally as indicated at 51 through an aperture 52 formed

in the cabinet end wall 12. The aperture 52 is made with a diameter exceeding the width of the member 50 by an amount equal to the amount the shelf is to be permitted to move. The inclination of the shelf 6 and the location of the pivot shaft 49 are preferably so chosen as to normally dispose the center of gravity of the roll 4 rearwardly of the pivot shaft 49, whereby the weight of the roll 4 serves to normally and continuously urge the shelf 6 to the position illustrated in Fig. 5. When the roll 4 is nearly exhausted, the center of gravity thereof will have shifted forwardly somewhat and movement of the shelf 6 to the position illustrated in Fig. 5 may, under these conditions, be insured as by securing to the rearward edge of the shelf 6 a suitable counterweight 53.

It will be noted that the counterweight 53 and the weight of the roll 4 cooperate to effect an automatic lifting of the fingers 47 to permit the roller 5 to be spring returned to its initial position immediately upon the severing of the withdrawn length of material. The shelf 6 is so nearly balanced that when a downward withdrawing force is applied to the end 6a of the sheet material, the shelf 6 will thereby be tilted to its lower position which is illustrated in Fig. 4.

In case it is desired to provide for a manual releasing of the stop means instead of the automatic releasing operation above described, the effect of the weight of the roll 4 and the counterbalance 53 may be offset as by means of a tension spring 54 which is extended between the member 50 and the bottom wall of the cabinet 1. When the spring 54 is employed, the roller 5 is not released upon severing of the withdrawn length of material and the shelf 6 must be manually tilted against the force of the spring 54 in order to effect the release of the roller 5. Accordingly, the member 50 after being turned outwardly through the aperture 52 as shown at 51 is bent forwardly to form a horizontally positioned outwardly extending finger-piece 55. Application of an upwardly directed pressure to the finger-piece 55 will pivotally move the shelf 6 about the pivot shaft 49 from the position illustrated in Fig. 4 to that illustrated in Fig. 5, whereupon the roller 5 is released and returned to its initial position by the spring 43. Thereafter an additional length of sheet material may be withdrawn from the dispenser and severed from the remainder in the manner previously described.

I have found that if the sheet material is violently withdrawn from the dispenser the momentum imparted to the roll of material 4 will cause the same to rotate through a part of a revolution after the actual feeding of the material is arrested. In order to prevent this additional material from passing outwardly through the slot 9 and so increasing the length of the next sheet withdrawn from the cabinet, I employ a spring pressure finger 55a best illustrated in Fig. 2. The finger 55a may form a continuation of the guiding shoe 7 and is preferably centrally disposed so as to overlie the center curved finger 47. The natural resilience of the material employed for the finger 55a is used to urge the finger into light pressure engagement with the surface of the roller 5. The finger thus serves to maintain adequate friction engagement between the sheet material and the roller during the time the sheet material is being withdrawn from the cabinet.

Upon tearing off the sheet material, the lift-

ing of the finger 47 serves to lift the spring finger 55a out of engagement with the roller and so permits the roller to return to its initial position. Any excess material which may be fed from the roll 4 of sheet material accumulates as a fold or loop between the roll 4 and the upper end of the spring finger 55a and so is included in the amount of sheet material which is measured by the device during the next withdrawal of sheet material.

The apparatus above described permits the dispenser to be used under widely varying circumstances by virtue of the provision which is made for adjusting the length of the sheet which may be withdrawn from the dispenser and also by virtue of the arrangement of the tilttable shelf 6 provided for either an automatic or a manual release of the stop member. Under these circumstances it is anticipated that the dispenser will, in many circumstances, be mounted in locations where it will be exposed to the action of the elements and the cabinet is for this reason preferably made weather-proof, being formed of sheet metal or other equally suitable material.

The hinged cover 2 is preferably positioned within the cabinet 1 so that the portion of the cover 2 which is disposed above the pivot pin 3 is telescoped within the cabinet 1 and occupies a position such as that indicated by dotted line 56 in Fig. 2. To prevent moisture entering between the cover 2 and the cabinet 1 at points disposed below the pivot pins 3, the side edges 57 of the cover 2 are flanged outwardly as indicated at 58 in Figs. 1 and 2 to overlie the side walls 11 and 12 of the cabinet. Thus, water falling on the cabinet 1 or the cover 2 must, in order to enter the interior of the cabinet, run uphill between the adjacent overlying portions of the cabinet 1 and cover 2.

Attention is directed to the fact that the tilttable shelf 6 and the roller 5 are both supported from the cabinet 1, whereas, the cutting member 36 and the guide member 7 are both carried by the cover 2. Thus, the difficulties encountered in previous dispenser constructions with respect to the necessity for threading the end of the material between rollers and guides upon the placing of a new roll of material within the dispenser is, in my device, avoided. By merely pivotally moving the cover 2 to an open position, the roll of sheet material 4 may be placed in a position resting upon the roller 5 and the shelf 6 and the end of the material may be merely passed over the top of the roller 5. Movement of the cover 2 to a closed position will dispose the parts in the positions illustrated in Fig. 2 and the device is ready for use.

Any suitable means may be employed for non-rotatably securing the end 13 of the shaft 10 to the adjustment lever 15 and for similarly securing the end 26 of the track defining member 25 to the end bracket 28. However, the squared end and square socket construction illustrated or other readily disengageable connection is preferred because it provides for the ready removal of the roller 5 from the cabinet. Such removal is effected by merely springing the bracket 28 to the right as viewed in Fig. 3 a distance sufficient to free the squared end 26 from the aperture 27, whereupon the roller 5 may be bodily lifted from the cabinet.

From the foregoing it will be observed that I have provided a dispenser for rolled sheet material wherein the withdrawing of the material operates the control roller to measure the

amount of material withdrawn and to arrest further withdrawing of the material when a predetermined length thereof has been withdrawn. This length may be adjusted as desired by means of the adjusting mechanism which is controlled by the control lever 15.

It will also be noted that the device is susceptible of either automatic or manual operation; that is, in the latter case a manual lifting of the member 55 is required before a second length of sheet material may be withdrawn from the cabinet, whereas, in the first instance the mere severing of the withdrawn length from the bulk of the material operates to automatically release the stop member and to permit another length to be immediately withdrawn.

While I have shown and described the preferred embodiment of my invention, I do not desire to be limited to any of the details of construction shown or described herein, except as defined in the appended claims.

I claim:

1. In a dispenser for rolled sheet material, the combination of: a cabinet for enclosing a roll of said sheet material and having an opening through which said material may be withdrawn; a movable means carried by said cabinet and frictionally engaging said sheet material for limited movement thereby between an initial position and an arresting position in which said material is frictionally held against further withdrawal; spring means normally urging said movable means to said initial position; and means for disengaging said material from said movable means to thereby permit said spring means to return said movable means to said initial position after movement thereof to said arresting position.

2. In a dispenser for rolled sheet material, the combination of: a cabinet for enclosing a roll of said sheet material and having an opening through which said material may be withdrawn; cutter means carried by said cabinet for severing a withdrawn length of said material; a movable means carried by said cabinet and frictionally engaging said sheet material for limited movement thereby between an initial position and an arresting position in which said material is frictionally held against further withdrawal; spring means normally urging said movable means to said initial position; and means responsive to severing of the withdrawn length of said material for disengaging said material from said movable means to thereby allow said spring means to return said movable means to said initial position.

3. In a dispenser for rolled sheet material, the combination of: a cabinet for enclosing a roll of said sheet material and having an opening through which said material may be withdrawn; a movable means carried by said cabinet and frictionally engaging said sheet material for limited movement thereby between an initial position and an arresting position in which said material is frictionally held against further withdrawal; spring means normally urging said movable means to said initial position; and manually operable means for disengaging said material from said movable means to thereby permit said spring means to return said movable means to said initial position.

4. In a dispenser for rolled sheet material, the combination of: a cabinet for enclosing a roll of said sheet material and having an opening through which said material may be withdrawn; a roller carried by said cabinet in a position to

normally frictionally engage said roll of sheet material and about which said material is passed in being drawn through said opening; means mounting said roller for limited rotational movement between an initial position and an arresting position in which said material is frictionally held against further withdrawal; spring means normally urging said roller to said initial position; and means for disengaging said sheet material and said roll of said material from said roller to permit said spring means to return said roller to said initial position after being moved to said arresting position.

5. In a dispenser for rolled sheet material, the combination of: a cabinet for enclosing a roll of said sheet material and having an opening through which said material may be withdrawn; a roller carried by said cabinet in a position to frictionally engage said roll of sheet material and about which said material is passed in being drawn through said opening, said roller having a plurality of circumferentially extending grooves formed in the outer surface thereof; an inclined shelf disposed within said cabinet in a position to normally support said roll of sheet material in said position frictionally engaging said roller; a plurality of fingers carried by said shelf disposed in partial encircling relation with said roller and between said roller and said material, said fingers being received within said circumferentially extending grooves; means mounting said roller for limited rotational movement between an initial position and an arresting position in which said roll of sheet material is frictionally held against further withdrawal; spring means normally urging said roller to said initial position; means pivotally supporting said inclined shelf for movement from an engaging position in which said fingers are disposed in said grooves below the surface of said roller to a releasing position in which said fingers engage said roll and said sheet material and lift the same out of engagement with the surface of said roller; and means for pivotally moving said shelf.

6. In a dispenser for rolled sheet material, the combination of: a cabinet for enclosing a roll of said sheet material and having an opening through which said material may be withdrawn; a roller carried by said cabinet in a position to frictionally engage said roll of sheet material and about which said material is passed in being drawn through said opening, said roller having a plurality of circumferentially extending grooves formed in the outer surface thereof; an inclined shelf disposed within said cabinet in a position to normally support said roll of sheet material in said position frictionally engaging said roller; a plurality of fingers carried by said shelf disposed in partial encircling relation with said roller and between said roller and said material, said fingers being received within said circumferentially extending grooves; means mounting said roller for limited rotational movement between an initial position and an arresting position in which said roll of sheet material is frictionally held against further withdrawal; spring means normally urging said roller to said initial position; means pivotally supporting said inclined shelf for movement from an engaging position in which said fingers are disposed in said grooves below the surface of said roller to a releasing position in which said fingers engage said roll and said sheet material and lift the same out of engagement with the surface of said roller; means normally urging said shelf to said

engaging position; and means for moving said shelf to said releasing position.

7. In a dispenser for rolled sheet material, the combination of: a cabinet for enclosing a roll of said sheet material and having an opening through which said material may be withdrawn; a roller carried by said cabinet in a position to frictionally engage said roll of sheet material and about which said material is passed in being withdrawn through said opening, said roller having a plurality of circumferentially extending grooves formed in the outer surface thereof; an inclined shelf disposed within said cabinet in a position to normally support said roll of sheet material in said position frictionally engaging said roller; a plurality of fingers carried by said shelf disposed in partial encircling relation with said roller and between said roller and said material, said fingers being received within said circumferentially extending grooves; means mounting said roller for limited rotational movement between an initial position and an arresting position in which said roll of sheet material is frictionally held against further withdrawal; spring means normally urging said roller to said initial position; means pivotally supporting said inclined shelf for movement from an engaging position in which said fingers are disposed in said grooves below the surface of said roller to a releasing position in which said fingers engage said roll and said sheet material and lift the same out of engagement with the surface of said roller; and means normally urging said shelf to said releasing position, said last named means being adjusted to be overcome by the pressure on said fingers resulting from withdrawal of said sheet material through said opening, whereby said shelf is moved to said engaging position.

8. In a mechanism for limiting to a predetermined length the amount of material which may be withdrawn from a dispenser for rolled sheet material, the combination of: a roller means mounted for rotary movement in a position to be frictionally engaged by said sheet material and moved therewith as said sheet material is withdrawn; a stationary path defining member defining a helical path; a movable member movable along said path; means on said roller for confining said movable member in said helical path and for moving said member along said path in response to rotation of said roller; and spaced stop means in said helical path for engaging said movable member and limiting the movement of said member to the portions of said helical path disposed between said stop means.

9. In a mechanism for limiting to a predetermined length the amount of material which may be withdrawn from a dispenser for rolled sheet material, the combination of: a roller means mounted for rotary movement in a position to be frictionally engaged by said sheet material and moved therewith as said sheet material is withdrawn; a stationary path defining member defining a helical path; a movable member movable along said path; means on said roller for confining said movable member in said helical path and for moving said member along said path in response to rotation of said roller; spaced stop means in said helical path for engaging said movable member and limiting the movement of said member to the portions of said helical path disposed between said stop means; and an adjustment means for moving said stop means along said helical path toward and away from each other.

10. In a mechanism for limiting to a predetermined length the amount of material which may be withdrawn from a dispenser for rolled sheet material, the combination of: a roller means mounted for rotary movement in a position to be frictionally engaged by said sheet material and moved therewith as said sheet material is withdrawn; a stationary path defining member defining a helical path; a movable member movable along said path; means on said roller for confining said movable member in said helical path and for moving said member along said path in response to rotation of said roller; spaced stop means in said helical path for engaging said movable member and limiting the movement of said member to the portions of said helical path disposed between said stop means, one of said stop means comprising a helical spring wound about said path defining member along a part of said helical path; and means for rotating said helical spring relative to said path defining member to thereby adjust the length of said helical path disposed between said stop means.

11. In a mechanism for limiting to a predetermined length the amount of material which may be withdrawn from a dispenser for rolled sheet material, the combination of: a roller means; shaft means mounting said roller for rotary movement in a position to be frictionally engaged by said sheet material and moved therewith as said sheet material is withdrawn; a stationary path defining member defining a helical path; a movable member movable along said path; means on said roller for confining said movable member in said helical path and for moving said member along said path in response to rotation of said roller; stop means at each end of said helical path for engaging said movable member and limiting the movement of said member to the portions of said helical path disposed between said stop means, one of said stop means comprising a helical spring wound about said path defining

member along a part of said helical path; and coacting means on said shaft means and on said helical spring securing said spring to said shaft means for non-rotating slidale movement therewith, whereby rotation of said shaft means relative to said path defining member moves said helical spring along said helical path to adjust the length of the portion thereof included between said stop members.

12. In a mechanism for limiting to a predetermined length the amount of material which may be withdrawn from a dispenser for rolled sheet material, the combination of: a roller means; shaft means mounting said roller for rotary movement in a position to be frictionally engaged by said sheet material and moved therewith as said sheet material is withdrawn; a stationary path defining member defining a helical path; a movable member movable along said path; means on said roller for confining said movable member in said helical path and for moving said member along said path in response to rotation of said roller; stop means at each end of said helical path for engaging said movable member and limiting the movement of said member to the portions of said helical path disposed between said stop means, one of said stop means comprising a helical spring wound about said path defining member along a part of said helical path; coacting means on said shaft means and on said helical spring securing said spring to said shaft means for non-rotating slidale movement therewith, whereby rotation of said shaft means relative to said path defining member moves said helical spring along said helical path to adjust the length of the portion thereof included between said stop members; adjustment means for rotating said shaft means relative to said path defining member to any desired angular position; and means for holding said shaft means in any angular position to which it may be moved.

RAY O. WILSON.
